BUILDING BLOCK AND CONSTRUCTION

Nathan Davidson, Los Angeles, Calif.

Application February 9, 1937, Serial No. 124,825

2 Claims. (Cl. 72—40)

My invention relates generally to building constructions involving the use of bricks or other building elements of a generally similar character, and particularly to a form of building element peculiarly adapted for beam and lintel construction.

It is an object of my invention to provide a building block construction which is exceptionally resistant to earthquakes, and which therefore has a wider range of applications and uses than building block construction heretofore used.

Another object of my invention is to provide a building element which has a ready utility in numerous types of construction and is particularly valuable in the construction of beams and lintels.

In bond beams, especially, it is desirable to have the reinforcing steel nearer the outer faces of the wall or beam than is possible with ordinary bricks or blocks, and to also have the steel completely surrounded with mortar. As will be seen hereinafter, both of these requirements are fully met by structures employing the novel building element of this invention.

Another advantage of my invention resides in the fact that I secure the aforementioned objects without in any way sacrificing the natural beauty of brick construction.

These and other objects and advantages will become apparent from the following description of a preferred form of my invention and from an inspection of the accompanying drawing in which:

Fig. 1 shows one form of bond beam construction;

Fig. 2 shows a modified form of bond beam or longitudinal tie construction;

Fig. 3 shows a form of lintel construction;

Fig. 4 shows a modified form of lintel construction;

Fig. 5 illustrates one method of overlapping the reinforcing steel; and

Fig. 6 is a perspective of my novel form of building element used in the foregoing construction.

Referring now to the drawing and particularly to Fig. 6 thereof, the numeral 10 indicates generally an L shaped building element which I will for descriptive purposes term an angle block. This block is formed of two sides 11 and 12, preferably at right angles to each other, although for particular uses this angle may be varied slightly either above or below 90°. The length of the angle block may of course be varied within reasonable limits, although from a practical stand-

point I find it advisable to make the block length equal that of the standard sized bricks with which it is to be used, this length being usually 8 1/4 inches, it being understood of course that the standard length for common brick varies somewhat in different localities due to climatic and other reasons, and further that in some districts bricks of special configuration and lengths sometimes up to as high as 12" are quite generally used. Consequently, the length of my angle brick will in general vary in accordance with the type of bricks with which it is to be associated in a given brick structure, and when in the specification and claims I use the term standard-sized brick, it is to be understood as including all sizes of bricks which now have, or may in the future have, a general usage in the building of brick masonry structures. The width of the sides 11 and 12 make likewise vary according to the size of the bricks used in the particular structure, but as a general rule I find it advisable to make one side, say the side 11 in Fig. 6, substantially the same width as the outside face width of its associated bricks, while the other side, as 10, may be the same width or somewhat smaller. Common bricks have been pretty well standardized in this country at 2 1/4 x 3 3/4 x 8", while numerous special type bricks are also used which have widths varying from 2 1/4 to 4" on one or both lateral faces. Since common bricks and special bricks are often used together in the same structure, I have found that an extremely efficient angle block is provided when it is formed with one side substantially the same width as the narrow face of a common brick and one side substantially the same width as the broad face of a common brick. This permits the block to be used interchangeably with common bricks no matter how they are laid, and also permits it to be used with most varieties of special brick without modification of either. The sides 11 and 12 can be made of any convenient thickness in proportion to the widths and length of the block, for most uses it being found that a thickness of from 1/2" to 1" is satisfactory, with the thickness at the heel of the joint or apex of the angle being sometimes thicker than at the outside, so as to give added strength at this point.

As will be apparent, the angle block 10 may be made from different materials, but I prefer to make it of brick clay and fire it in the usual manner employed in the manufacture of bricks.

Referring now to Fig. 1, wherein is illustrated one form of bond beam employing the building element illustrated in Fig. 6, the numerals 13

and 14 indicate generally two opposing spaced walls laid up in the usual fashion with building elements such as bricks which are set in mortar in known manner. The numeral 15 indicates 5 the bricks used in forming the walls, and they may be common brick or special type bricks, such for instance as those illustrated in my prior Patent No. 2,060,045 issued November 10, 1936.

In this type of beam, as in most beams for 10 that matter, it is desirable to have the horizontal steel 16 as near the outside of the wall and beam as possible and directly under the brick courses so as to get the full bonding and reinforcing effect of the steel on the entire structure and to allow beams of a greater depth to be used. Consequently, angle blocks 10 are substituted for the bricks at the four corners of, or edges of the beam and the steel is placed in the enlarged space formed by the angle. This 15 substitution is however performed by steps, the course of angle blocks 10a being laid on the course of bricks indicated as 15a, with a corresponding offset course 10b of angle blocks laid in the same horizontal plane, the intermediate 20 course corresponding to the rear or backing wall being formed of bricks. The horizontal steel rods 16a and 16b are then placed in position after the requisite amount of mortar has been placed in the joints and one or more courses of 25 bricks are then laid on each of the beam courses and thoroughly bonded with mortar to carry the beam up to its required height.

The upper outside courses of the beam are then laid using angle blocks 10c and 10d, with 30 a center course of bricks between them. The steel rods 16c and 16d are then placed in position and the joints and spaces surrounding the rods are thoroughly filled with mortar. If it is desired to carry the walls 13 and 14 up beyond 35 the bond beam, opposing courses of bricks are laid in the usual manner.

In Fig. 2 I have illustrated a bond beam or wall tie constructed in the same manner as that shown in Fig. 1 except that the beam portion of 40 the wall is not enlarged or offset. In this case the angle blocks 10a and 10b are laid without an intermediate course of bricks between them, and the steel rods 16a and 16b are therefore closer together and separated only by mortar. If additional strength against shear is desired, 45 lateral steel or wire ties 17, preferably with bent ends, may be used to restrict the lateral movement of the reinforcing bars 16.

As before, one or more courses of brick are 50 then laid up in mortar on the angle blocks 10a and 10b, and angle blocks 10c and 10d with their respective steel reinforcing rods are then laid as before. The wall can then be carried on up in known manner if desired.

The angle blocks of my invention are also 55 peculiarly well adapted for lintel construction as will be seen from Figs. 3 and 4 which illustrate typical construction for different sized walls.

The construction of Fig. 3 is quite similar in 60 form to the beam construction of Fig. 1 and for simplicity the elements will therefore be given the same descriptive numerals, it being understood of course that in forming lintels, a temporary support such as a plank or other flat 65 surface is employed to support the brick construction until the mortar has set.

The numerals 10a and 10b again indicate 70 spaced courses of angle blocks, having a course of bricks 15 between them. Horizontal rein-

forcing rods 16a and 16b are bedded in mortar in the enlarged space of the angles as before and the required number of courses of bricks 15 are laid over the lintel courses. For maximum strength, steel cross ties 17 with bent ends 5 are laid at intervals along the lintel course to further support and tie in the horizontal steel 16 which runs longitudinally of the structure. The vertical and horizontal strength of the lintel may be further increased by placing vertical 10 steel rods or stirrups 18 at intervals between opposed wall courses and thoroughly embedding them in mortar. The lower ends of the stirrups should preferably be bent and hooked around the cross ties 17 to assist in distributing 15 the load throughout the vertical extent of the lintel and wall structure although this is not essential.

In Fig. 4 I have illustrated a lintel construction 20 which is similar in form to the beam of Fig. 2. It will be seen that this form varies from that of Fig. 3 only in the fact that no intermediate course of bricks is laid between the angle block courses 10a and 10b which again form the lower face of the lintel. Lateral ties 17 are preferably 25 employed in this form also, as well as vertical stirrups 18.

Where beams or lintels of considerable length are constructed it is necessary to overlap the horizontal reinforcing steel, since it comes in lengths 30 less than the whole wall length. It will be apparent that adequate lapping should be had to insure full strength of the beam, and in Fig. 5 I have illustrated one very suitable method of lapping the steel so that no strength is sacrificed at the 35 joint. One of the rods indicated by the numeral 16n is bent adjacent one end, so that the end is parallel to, but offset from the body of the rod. The other rod indicated by the numeral 16p is then laid parallel to the offset end of rod 16n 40 and in close proximity thereto, preferably coaxial with the main portion of the rod 16n.

Wherever I have used the term mortar herein, 45 it is to be understood as comprehending mortar in its broadest sense and not as limited to mortar of any particular ingredients or degree of plasticity or fluidity. It is also to be understood that the structures illustrated in the drawing are merely typical of preferred forms of construction embodying my invention and that I do not 50 mean to be limited to the precise forms shown, since my invention is susceptible of use in many and varied types of architecture and building construction.

I claim as my invention:

1. A building construction of the class described comprising a plurality of substantially vertical wall sections formed of courses of standard sized bricks, said bricks being joined together with mortar, one or more of said wall sections having 60 a course of rectangular angular blocks provided with outside faces substantially corresponding in size with standard bricks and laid with their angular faces toward the midwidth of the wall, the space thus defined lying between the vertical 65 faces of at least one of said wall sections and being substantially filled with mortar, and a horizontally extending metallic reinforcing rod imbedded in said mortar in said space in vertical alignment with the courses of bricks of one wall 70 section.

2. A wall construction of the class described comprising a plurality of parallel wall sections of standard sized bricks with mortar bonding together said bricks, at least two of said sections 75

having opposed courses of angle blocks provided with outside faces substantially corresponding in size with standard bricks and in association with the standard bricks, said angle blocks being laid in said opposed courses to provide a longitudinally extending space in each course which lies

between the side faces of the section containing said course, a longitudinally extending reinforcing rod disposed in the said space in each of said sections, and mortar filling said spaces to surround said rods.

NATHAN DAVIDSON.
